UNITED STATES PATENT OFFICE

110,722

DESIGN FOR A ROLLER SKATE

Alexander F. Kaptuller, Chicago, Ill., assignor
to Allied Engineering Company, Chicago, Ill.,
a corporation of Illinois

Application December 16, 1937, Serial No. 73,654

Term of patent 14 years

To all whom it may concern:

Be it known that I, Alexander F. Kaptuller, a citizen of Germany, residing at Chicago, in the county of Cook and State of Illinois, have invented a new, original, and ornamental Design for a Roller Skate, of which the following is a specification, reference being had to the accompanying drawing, forming part thereof.

In the drawing—

Fig. 1 is a plan view of a roller skate embodying my new design;

Fig. 2 is a side elevational view;
Fig. 3 is a front elevational view; and
Fig. 4 is a rear elevational view of the roller skate.

I claim:

The ornamental design for a roller skate, substantially as shown.

ALEXANDER F. KAPTULLER.
